COUNTER STOOL OR SIMILAR ARTICLE

Maurice P. Burke, 5140 N. Westmoreland Road,
Dallas, Tex.

Filed Jan. 22, 1962, Ser. No. 68,402

Term of patent 14 years

(Cl. D15—8)

FIG. 3.

FIG. 4.

FIG. 5.

FIGURE 1 is a side elevational view of a counter stool or similar article showing my design;

FIG. 2 is an elevational view taken in the direction of the arrow 2 of FIG. 1;

FIG. 3 is an elevational view taken in the direction of arrow 3 of FIG. 1 and with the seat portion removed for convenience of illustration;

FIG. 4 is a top plan view of the bracket shown in FIG. 3; and

FIG. 5 is a bottom plan view thereof.

The dominant features of my design reside in those portions shown in full lines on the drawing.

I claim:

The ornamental design for counter stool or similar article, substantially as shown and described.
